UNITED STATES PATENT OFFICE.

HENRY L. DE ZENG, OF GENEVA, NEW YORK, ASSIGNOR TO DE ZENG STANDARD COMPANY, OF CAMDEN, NEW JERSEY, A CORPORATION OF NEW JERSEY.

DIAGNOSTIC INSTRUMENT.

Application filed March 5, 1925. Serial No. 13,235.

This invention relates to improvements in diagnostic instruments, and has particular reference to an improved illuminating and reflecting instrument principally adapted for examining the orifices of the body, such as throat, nose, etc.

An important object of the present invention is the provision of an illuminator and a reflector so arranged as to be capable of insertion into the mouth or other openings of the body for the purpose of making observations or illuminating operations.

Another object is to provide such a device with a member capable of depressing the patient's tongue to keep it out of the way when making a diagnosis or performing an operation.

Another object is to provide such a device which will not be uncomfortable or injurious to the tongue or other parts with which it comes in contact.

Still another object is to provide such a device with a reflector so disposed that a view of the back nasal passages may be easily had by the operator without necessitating the use of other means.

Still another object is to provide such a device which may be easily dismantled for the purpose of sterilizing, etc.

Another object is to provide such a device in which illumination of varying intensity may be had in accordance with the nature of the work being done.

Another object of the invention is to provide such a device which will be simple in construction, strong and durable in service and an improvement in the art.

Another object is to provide a diagnostic instrument with a source of illumination, and a plurality of interchangeable attachments adapted to be selectively used therewith, more particularly the provision of a tongue depressor and laryngoscope adapted for interchange.

With these and other objects in view, the invention resides in the novel features of construction, combination and arrangement of parts hereinafter set forth, illustrated in the accompanying drawings and specifically pointed out in the appended claims.

In the accompanying drawings, wherein is shown the preferred embodiment of the invention for the purposes of illustration:

Figure 1 is a side elevation of a diagnostic instrument embodying the invention;

Figure 2 is a top plan view thereof;

Figure 3 is a vertical longitudinal sectional view on the line 3—3 of Figure 2;

Figure 4 is a transverse sectional view on the line 4—4 of Figure 1;

Figure 5 is a detail perspective view of the laryngoscope detached from the holder;

Figure 6 is an elevation of a modified form of illuminating head;

Figures 7 and 8 are detail sectional views illustrating a form of interchangeable mirror mounting for the laryngoscope;

Figure 9 is a detail perspective view of the tongue depressor plate adapted for interchange with the laryngoscope.

In carrying out the invention a handle member 10 is provided which may be of the form adapted to contain a battery or which may be adapted for detachable connection to some other source of electrical energy as is well known in the art.

At the upper end of the handle member 10 is a threaded extension 11 (Figure 3) preferably of a reduced diameter, said extension being adapted to receive the internally threaded head 12. A knurled nut 13 is also operative upon the threaded extension 11 and adapted to be screwed down against the top cap 9 of the handle 10 to close the circuit to light the lamp.

The head member 12 is provided with an offset extension 14, as best shown in Figures 1 and 3, this extension being suitably formed to provide a guide way 15 for the interchangeable reception of either a tongue depressor blade or a laryngoscope, as desired. Overlying the offset member 14, and preferably secured thereto is a conduit 16 which is adapted at its extremity to receive the butt of an incandescent lamp 17. An electrical conducting wire 18 passes through the conduit 16 and the head member 12 and carries at its extremity the terminals 19 which are suitably insulated by the bushings 20 and 21. From this it will be apparent that the wire 18 and its terminals 19 form one side of the electric circuit from the battery or other source of energy, and the conduit 16, head 12, and associated parts, all being of metal forming the other side of the circuit which contacts with the outer shell 22 of the lamp butt.

In the form of the invention shown in Figures 1 and 3, the offset extension is shown as disposed at an acute angle to the

axis of the head member 12, but I do not limit myself to this angular disposition, since it may be a right angle or obtuse angle if desired. For example, as shown in 5 Figure 6, the blade receiving member 14^a is mounted perpendicular to the axis of the head 12^a.

A laryngoscope attachment blade 23 is adapted to extend from the head member 12, 10 and, as best shown in Figure 5, it has one enlarged extremity 24 which is curved for a portion of its length, the amount of curvature being greater than the thickness of the guide way 15. In this way the enlarged extremity 24 may be inserted within the guide way 15, and because of its resilient nature it will be frictionally held so as not to be capable of accidental displacement. At the 15 end, opposed from the enlargement 24, the blade 23 is offset as at 25 and provided with a suitable reflector 26 which is so proportioned and mounted that when the blade is inserted in the guide way 15 the reflector will be in line with the light coming from 20 the lamp 17. The reflector may be plane, as shown at 26 in Figure 7, or it may be concave as at 26^a in Figure 8. In commercial application of the invention a laryngoscope blade 23 will be sold with a plurality of reflectors, some plane and some concave, and some being larger in diameter than others. 25 In order to facilitate interchanging of reflectors, the arm 23 carries a stud 27, to which the reflector casing 28 may be screwed.

A sleeve 29 is mounted slidably upon the extremity of the conduit 16, and carries a condensing lens 30 of any suitable type, thus forming at one time a light concentrating 40 and focusing device. By adjusting the sleeve 29 axially the intensity of the illumination directed towards the reflector 26 may be varied, as will be obvious.

In use, the operator grasps the handle 10 and inserts the laryngoscope attachment blade 23 into the guide way 15, having first selected the proper size of reflector, either 45 plane or concave. The reflector 26 may then be inserted in the patient's mouth for the purpose of making observations and as has been previously stated, the condensing lens 30 may be adjusted to give the proper 50 intensity of illumination by varying the vergency of the light rays as desired. In view of this simple construction the laryngoscope attachment blade may be easily detached and sterilized after it has been used, which, of course, is very necessary; and also, in view 55 of its frictional engagement in the guide way 15, it may be adjusted longitudinally

so as to move the reflector toward or away from the lamp if desired.

In Figure 9 a tongue depressor blade 31 is illustrated, it being interchangeable with the laryngoscope blade in its application to the 65 illuminating head. It is formed from a piece of suitable sheet metal, and one of its ends 32 is of approximately the same size and longitudinal curvature as the end 24 of the laryngoscope, while its other end is also 70 widened, and curved in the opposite direction, as shown at 33. When the blade 31 is affixed to the illuminating head, it may be inserted in a patient's mouth and the end 33 used to depress the tongue, for the purpose of examining the throat, relieving gagging, etc., as is well known to those skilled 75 in the art.

From the foregoing it will be apparent 80 that an improved instrument has been devised which will be especially valuable to practitioners such as throat and nose specialists, etc., said device being of a simple construction and such that it will give efficient service. Obviously, changes may be made 85 in the minor details of construction and arrangement of parts, and the right is herein reserved to make such changes falling within the scope of the appended claims without departing from the spirit of the invention. 90

Having thus described my invention, I claim:

1. In a device of the character described, a handle, a head on the handle having an offset arm with a longitudinal slideway thereon, a lamp adjacent the end of the arm, a slide having a condensing lens over the lamp, a resilient sheet stock blade adapted to fit in the slideway on the arm and having a displacement transverse to the slideway, 100 and a mirror adjacent the other end of the blade, the said displacement of the blade being adapted to increase the resilient friction of the blade in the slideway and said lens slide being adapted to be moved with 105 respect to the lamp to focus the light on the mirror.

2. For use in combination with the offset arm of a diagnostic instrument having a longitudinal slideway, a resilient sheet stock 110 instrument blade having one end shaped to fit the slideway and having an internal cut out portion intermediate the sides fitting the slideway adapted to increase the resilience 115 of the joint portion and a displacement transverse to the plane of the blade at the joint portion adapted to insure the resilient frictional engagement of the blade with the slide-way.

HENRY L. DE ZENG.
